HOT BLAST CUPOLA

Clarence D. Barr and Dan Owen Holmes, Birmingham, Ala., assignors to American Cast Iron Pipe Company, Birmingham, Ala., a corporation of Georgia

Application August 17, 1935, Serial No. 36,744

10 Claims. (Cl. 266—14)

The present invention relates to improvements in hot blast cupolas and resides principally in the provision of means for circulating, heating and delivering air under pressure to the tuyères 5 which blast the air into the cupola to effect melting of the products therein used in the production of cast metal objects.

One of the principal objects of the present invention is to provide a relatively long path of circulation of the air subject to the heat created in the cupola during melting of the metals whereby the air is thoroughly heated before it is delivered to the tuyères.

Another object of the invention resides in a special construction of conduits through which the air is circulated and providing for easy replacement of the conduits when necessary.

A further object of the invention resides in the provision of means for readily determining during operation of the cupola, that is, during a melting operation, whether the respective conduits are intact or whether leaks have occurred therein, and providing for cutting out or making inoperative such of the conduits as may be leaky 25 so that should one or more of the conduits become burned out or develop leaks the air will not be permitted to escape therefrom into the cupola to create a melting zone above the desired melting zone created by the tuyères.

The foregoing and other objects and advantages of the invention will become more apparent and will be pointed out during the course of the following detail description of the drawings, in which

Fig. 1 is a vertical central sectional view through a cupola embodying the present invention and taken on the line 1—1 of Fig. 2;

Fig. 2 is a view taken on the line 2—2 of Fig. 1;

Fig. 3 is an enlarged fragmentary view of the upper portions of two pairs of conduits and their couplings, one pair being shown in section;

Fig. 4 is an enlarged fragmentary view partly in section through a portion of the upper end of the cupola and showing the manner of hinging the conduits;

Fig. 5 is an enlarged detail view partly in section and partly in elevation showing the lower ends of the conduits, the inlet and outlet pipes with which they communicate and valves for controlling the flow of air through said conduits; and

Fig. 6 is a front view of one of the covers for the bustle pipes taken on the line 6—6 of Fig. 5.

In Fig. 1 of the drawings the numeral 1 indicates the lining of the base of the cupola composed of refractory material enclosed within a metal shell 2 resting upon a mantle plate 3.

The usual tuyères 4 communicate with openings 5 through the lining 1 to deliver the blasts

of air into the cupola to effect the melting of the metal therein. Each of the tuyères communicates with a down pipe 6, the upper ends of which pipes are connected to and communicate with the lower bustle pipes 7.

The inner or refractory wall 8 of the cupola, above the base, is formed to accommodate conduits or pipes 9 and 10 arranged in pairs with the longer pipes 9 of each pair communicating at their lower ends with the lower bustle pipes 7; and with the shorter pipes 10 communicating with the upper bustle pipes 11 to which the air under pressure is supplied from any suitable source, not shown. It will be noted that the lower ends of the pipes 9 and 10 extend through openings in the refractory lining 8 and the outer shell 12 of the cupola, and as shown best in Fig. 5, confront respectively valve heads 13 and 14 located respectively in the lower and upper bustle pipes 7 and 11. Around the lower ends of each pipe 9 and 10 within the said bustle pipes is a suitable gasket 15 capable of withstanding the temperatures to which they are subjected, due to the passage of the air therethrough and the heat of the cupola, and adapted to be compressed by gland rings 16 drawn up against the gaskets by means of bolts 17 and nuts 18 to effect a fluid tight joint on each conduit, while permitting movement of the conduits under forces created by expansion and contraction.

The valve heads 13 and 14 are carried on stems 19 each provided at its outer end with a handle 20. The stems extend through gland nuts 21 threaded onto the outer ends of bosses 22 through which and packings 23 the stems also extend. The bosses 22 which receive the stems 19 are provided on plates 24 covering the respective bustle pipes. The said cover plates 24 are removably attached to the bustle pipes by eye bolts 25, the outer ends of which receive wing nuts 26. Dowel pins 26' are provided to center the cover plates. Packing rings 27 are inserted between the plates 24 and the bustle pipes to provide fluid tight joints.

The direction of flow of the air through the bustle pipes, conduits 9 and 10 and the tuyères is indicated by the arrows in the drawings, it being noted that the air enters the shorter pipes 10 from the bustle pipes 11 and then passes upwardly within the cupola wherein the pipes are directly exposed to the temperatures existing in the cupola, and then down through pipes 9, bustle pipes 7, down pipes 6, and through the tuyères 4 into the cupola through the openings 5 to create the melting zone at the bottom of the cupola.

Referring to Figs. 1 and 2 it will be noted that the respective conduits 9 and 10 are alternately arranged around the interior of the cupola, and, of course, the number of conduits used depends

upon the capacity of the cupola, and the size of the conduits used.

Each pair of conduits 9 and 10 is connected to its top by couplings 28, shown in detail in Figs. 5 3 and 4, each coupling comprising a hood-like member having a pair of sockets 29 and 30 therein which receive the upper ends of the pipes 9 and 10. Packing rings 31, somewhat similar to piston rings, are seated in grooves in the upper ends of 10 the conduits and contact the inner walls of the sockets 29 and 30, providing fluid tight joints, and yet permitting relative longitudinal movements between the conduits and sockets to take care of expansion and contraction which occurs 15 at various times in the melting process and thereafter.

Each of the couplings 28 is provided with up-standing ears 32 having aligned openings to receive pins 33 maintained against longitudinal movement by means of cotter pins 34, or the like. Depending brackets 35 are attached to the annular plate 36 at the top of the cupola as by means 20 of rivets or bolts 37, the said brackets being formed to provide cradles 38 to receive pins 33 to 25 hingedly connect each pair of pipes 9 and 10, and their respective couplings 38, to the top of the cupola.

As is well known hot blast cupolas are charged by dumping the iron, coke, etc., thereinto from 30 the top. In the present case, since the conduits 9 and 10 and couplings 28 especially at their tops are exposed to contact by the iron and coke being dumped into the cupola, we provide guard plates 40 each having at its top a hooked end or flange 35 41 to engage over the plate 36 whereby the plates 40 are removably supported to protect the upper ends of the conduits and their couplings during charging of the cupola.

From the foregoing it should be obvious that 40 the air under pressure which is supplied to the bustle pipes 11, is forced upwardly through conduits or pipes 10, couplings 28, and downwardly through conduits or pipes 9, into the lower bustles 7 and down pipes 6 to the tuyères. The travel of 45 the air is over a relatively long course with the conduits in direct exposure to the heat within the cupola, so that the air which is delivered to the tuyères and blasted into the cupola is of a relatively high temperature.

Of course the air entering the bustle 11 is inducted into the lower ends of the pipes 10, while 50 the air delivered from the pipes 9 into the bustle 7 is emitted under pressure toward the valve heads 13. The operator may test from time to time 55 whether or not the pipes 9 and 10 and their couplings are intact or whether they have developed leaks by moving the valve heads 13 toward the confronting ends of the pipes 9. If the valve heads move against their respective pipes with 60 ease, then the operator will know or be warned that there is a leak in one of the pipes 9 or 10 of the pair being tested. In such event he simply 65 closes the valves 13 and 14 against their respective pipes so that the pipes thus closed are cut out and air will be delivered to the tuyères only through the intact pipes thus assuring maintenance of the melting zone at the bottom of the cupola.

When it is necessary to replace any of the pipes 70 after a melting operation and when the cupola has cooled sufficiently to permit a workman to enter it, he removes the guard plates 40 which cover the pipes to be repaired, as well as the refractory cement or filler C from the lower ends of said 75 pipes, swings the said set of pipes on the pivot 33

to the dot and dash line position of Fig. 1, after removing the gland rings 16. The conduits or pipes may be then readily withdrawn from the couplings and new ones inserted therein, after which the conduits are restored to the full line 5 position of Fig. 1. The packings 15 may then be placed around the lower ends of the conduits, the gland rings 16 restored, and a new batch of refractory cement C troweled in to fill the space 10 around the lower ends of the pipes. If the couplings 28 need to be repaired the pins 33 are simply moved out of the cradles 38 so that a new installation may be made in obvious manner.

We would point out also that access to the interior of the bustles for removing and replacing the 15 gland rings 16, is had simply by removing the proper plate 24 which carries the valve with it as a unit.

We have shown and described the pipes or conduits 9 and 10 arranged or coupled in pairs with 20 the inlet for the air through the lower bustle pipe so that the air is fed upwardly through the pipes 10 and then downwardly through the pipes 9. We have also shown and described slip joints 25 for the ends of said pipes to facilitate removal and replacement thereof.

What we claim is:

1. In a hot blast cupola having a chamber to receive a charge of materials to be melted therein and tuyères communicating with said chamber adjacent its lower end to deliver blasts of air thereto to create a melting zone at the bottom of the chamber, means to preheat the air delivered by said tuyères to said chamber comprising bustle pipes into which the air is 35 delivered under pressure, conduits leading from said bustle pipes upwardly within the cupola, a second set of conduits leading downwardly in said cupola, couplings connecting the upper ends of adjacent conduits and hingedly supporting the 40 same at their tops within said cupola, and bustle pipes communicating with said second conduits and said tuyères.

2. In a hot blast cupola having a chamber to receive a charge of materials to be melted therein 45 and tuyères communicating with said chamber adjacent its lower end to deliver blasts of air thereto to create a melting zone at the bottom of the chamber, means to preheat the air delivered by said tuyères comprising conduits on 50 the interior of the cupola and arranged in pairs with couplings at their upper ends, bustle pipes into which the air under pressure is delivered for heating, bustle pipes into which the heated air is delivered, one of the conduits of each pair 55 communicating with said first bustle pipes, and the other of the conduits of each pair communicating with the second bustle pipes, and said tuyères communicating with the second bustle pipes to receive the heated air therefrom and 60 deliver it into said chamber.

3. In a hot blast cupola having a chamber to receive a charge of materials to be melted therein and tuyères communicating with said chamber adjacent its lower end to deliver blasts of air thereto to create a melting zone at the bottom of the chamber, means to preheat the air delivered by said tuyères comprising conduits on the interior of the cupola and arranged in pairs with couplings at their upper ends, bustle pipes into which the air under pressure is delivered for heating, bustle pipes into which the heated air is delivered, one of the conduits of each pair 65 communicating with said first bustle pipes, and the other of the conduits of each pair communicating with the second bustle pipes, and said tuyères communicating with the second bustle pipes to receive the heated air therefrom and 70 deliver it into said chamber.

5 pipes, and the other of the conduits of each pair communicating with the second bustle pipes, said tuyères communicating with the second bustle pipes to receive the heated air therefrom and deliver it into said chamber, and a hinged connection for each pair of conduits permitting them to be swung inwardly in the cupola for the purposes specified.

4. In a hot blast cupola having a chamber 10 to receive a charge of materials to be melted therein and tuyères communicating with said chamber adjacent its lower end to deliver blasts of air thereto to create a melting zone at the bottom of the chamber, means to preheat the 15 air delivered by said tuyères comprising bustle pipes into which the air is delivered under pressure, conduits leading from said bustle pipes upwardly within the cupola, a second set of conduits leading downwardly in said cupola, couplings connecting the upper ends of adjacent 20 conduits and hingedly supporting the same at their tops within said cupola, fluid tight expansion joints between said couplings and conduits, and bustle pipes communicating with said second conduits and said tuyères.

5. The structure of claim 4 wherein the bustle 25 pipes are arranged externally around the cupola, with the lower ends of all conduits extending through the cupola wall in communication with the bustle pipes, and fluid tight joints are provided between said lower ends of the conduits and said bustle pipes.

6. In a hot blast cupola having a chamber 30 to receive a charge of materials to be melted therein and tuyères communicating with said chamber adjacent its lower end to deliver blasts of air thereto to create a melting zone at the bottom of the chamber, means to preheat the air delivered by said tuyères comprising bustle 35 pipes into which the air is delivered under pressure, conduits leading from said bustle pipes upwardly within the cupola, conduits leading downwardly in said cupola, couplings connecting the upper ends of said conduits in pairs and hingedly supporting the same within said cupola, bustle pipes communicating with said second 40 conduits and said tuyères, and valves within said bustle pipes confronting the open ends of said conduits and operable to permit circulation of air through said pairs of conduits and to cut off said circulation.

7. In a hot blast cupola having a chamber to receive a charge of materials to be melted therein and tuyères communicating with said chamber adjacent its lower end to deliver blasts of air thereto to create a melting zone at the bottom of the chamber, means to preheat the air delivered by said tuyères comprising bustle pipes into which the air is delivered under pressure, conduits leading from said bustle pipes upwardly within the cupola, conduits leading downwardly in said cupola, couplings connecting the upper ends of said conduits in pairs and hingedly supporting the same within said cupola, bustle pipes 55 communicating with said second conduits and said tuyères, and manually controlled means to determine the continuity of the passage of the air through said conduits and couplings and operable to close said conduits in the event of leakage to prevent delivery of air thereto.

8. In a hot blast cupola having a chamber to

receive a charge of materials to be melted therein and tuyères communicating with said chamber adjacent its lower end to deliver blasts of air thereto to create a melting zone at the bottom of the chamber, means to preheat the air delivered by said tuyères comprising bustle pipes into which the air is delivered under pressure, conduits leading from said bustle pipes upwardly within the cupola, conduits leading downwardly in said cupola, couplings connecting the upper 10 ends of said conduits in pairs and hingedly supporting the same within said cupola, bustle pipes communicating with said second conduits and said tuyères, removable closures on said bustle pipes and affording access to the interior thereof, removable packings around said conduits within said bustle pipes forming fluid tight joints between said bustle pipes and said conduits, and valves carried by said removable closures operable to close said conduits.

9. In a hot blast cupola having a chamber to receive a charge of materials to be melted therein and tuyères communicating with said chamber adjacent its lower end to deliver blasts of air thereto to create a melting zone at the bottom of the chamber, means to preheat the air delivered by said tuyères comprising bustle pipes into which the air is delivered under pressure, conduits leading from said bustle pipes upwardly within the cupola, conduits leading downwardly in said cupola, bustle pipes into which the heated air is delivered, couplings connecting the upper ends of said conduits in pairs and hingedly supporting the same within said cupola, the lower ends of said conduits being curved and extending through the wall of the cupola into the said bustle pipes, removable packings forming a fluid tight joint between said lower ends of the conduits and the bustle pipes, and removable closures on the bustle pipes affording access to the interior thereof for removal and replacement of said packings to permit said pairs of conduits to be swung on their hinges and to be clamped in place.

10. In a hot blast cupola having a chamber to receive a charge of materials to be melted therein and tuyères communicating with said chamber adjacent its lower end to deliver blasts of air thereto to create a melting zone at the bottom of the chamber, means to preheat the air delivered by said tuyères comprising bustle pipes into which the air is delivered under pressure, conduits leading from said bustle pipes upwardly within the cupola, conduits leading downwardly in said cupola, bustle pipes into which the heated air is delivered, couplings connecting the upper 55 ends of said conduits in pairs and hingedly supporting the same within said cupola, the lower ends of said conduits being curved and extending through the wall of the cupola into the said bustle pipes, removable packings forming a fluid 60 tight joint between said lower ends of the conduits and the bustle pipes, and removable closures on the bustle pipes affording access to the interior thereof for removal and replacement of said packings to permit said pairs of conduits to be swung on their hinges and to be clamped in place, and means between said removable closures and said bustle pipes to form a fluid tight joint when the closures are clamped onto said bustle pipes.
